UNITED STATES PATENT OFFICE.

WALTER F. KOKEN, OF ST. LOUIS, MISSOURI.

DESIGN FOR A BARBER'S CHAIR.

41,823.

Specification for Design.

Patented Oct. 3, 1911.

Application filed July 13, 1911. Serial No. 638,384. Term of patent 14 years.

To all whom it may concern:

Be it known that I, WALTER F. KOKEN, a citizen of the United States, residing at the city of St. Louis, State of Missouri, have invented a new, original, and ornamental Design for Barbers' Chairs, of which the following is a specification, reference being had to the accompanying drawings, forming part thereof.

Figure 1 of the drawings is a perspective

view of a barber's chair showing my new design; and Fig. 2 is a side elevation thereof.

I claim:

The ornamental design for a barber's chair as shown.

WALTER F. KOKEN.

Witnesses:

LOTTIE M. FOX,
BERTHA VON BEHRENS.
